(57) **CLAIM**

The ornamental design for pads for an automatic external defibrillator, as shown and described.

DESCRIPTION

FIG. 1 is a front plan view of pads showing our new design; and,

FIG. 2 is a rear plan view thereof.

The broken line showing of connecting tubes is for illustrative purposes only and forms no part of the claimed design.

1 Claim, 2 Drawing Sheets

FIG. 1

FIG. 2
